[57] CLAIM

The ornamental design for oropharyngeal airway, as shown and described.

DESCRIPTION

FIG. 1 is a right side elevational view of an oropharyngeal airway showing my new design;

FIG. 2 is a left end view;

FIG. 3 is a right end view;

FIG. 4 is a top plan view; and

FIG. 5 is a bottom plan view.

The left side elevational view is identical to the right side elevational view of FIG. 1.

FIG. 1

FIG. 2

FIG. 3

FIG. 4

FIG. 5
